UNITED STATES PATENT OFFICE.

ARTHUR E. BINNS, OF NORWICH, CONNECTICUT.

SUCTION APPARATUS FOR PAPER-MACHINES.

1,113,534.

Specification of Letters Patent.

Patented Oct. 13, 1914.

Application filed September 18, 1913. Serial No. 790,435.

To all whom it may concern:

Be it known that I, ARTHUR E. BINNS, a citizen of the United States, residing at Norwich, New London county, State of Connecticut, have invented certain new and useful Improvements in Suction Apparatus for Paper-Machines, of which the following is a full, clear, and exact description.

This invention relates to paper machines and particularly to an improved form of suction apparatus of the character set forth in my prior Patent No. 1,040,126 of October 1st, 1912.

The present invention aims to provide a more effective mechanical association of the various parts giving greater efficiency and durability. These and other advantages will be apparent from the following detailed specification taken in connection with the accompanying drawings forming part thereof and illustrating a preferable embodiment of the invention.

In these drawings: Figure 1 is a view in end elevation of a suction apparatus embodying the improved construction of the present invention. Fig. 2 is a top plan view of the suction apparatus shown in Fig. 1, parts being broken away. Fig. 3 is an end elevation of the parts shown in Fig. 2. Fig. 4 is a vertical section taken on the line 4-4 of Fig. 2, and on an enlarged scale. Figs. 5-6 are views in front elevation in vertical section of one of the suction cylinder heads. Figs. 7-8 are views in front elevation in vertical section of the other of said cylinder heads. Figs. 9-17 relate to details of construction.

Referring to the drawings by numerals, 1 designates, generically, the suction roll apparatus of the present invention, which apparatus is supported at its ends by bearings 2 and is adjustably carried in supporting standards 3.

4 designates the felt or web which is fed by a suitable roll 5 to and around the suction apparatus, 6 designating the couch roll of the paper making machine. The pulp is deposited on the felt or web 4 and is carried by said web around the cylinder of the suction apparatus which extracts the moisture therefrom.

The suction apparatus proper comprises a main suction cylinder 7 having its ends open and provided with a suitable number

of perforations therethrough extending longitudinally of the cylinder and about its periphery. This cylinder is provided at one end with a flange 8 having key-ways 8^a therein, a gear wheel 10 being suitably keyed to this flange 8. The opposite end of the cylinder is provided with a second flange 9. The ends of the cylinder are closed by non-rotatable heads 11 and 12, suitable packing 13 being interposed between the cylinder ends and said heads.

14 designates a center supporting roll for the cylinder, this roll being hollow and having end inserts 14^a providing a broad bearing surface, these inserts carrying spindles 15 which extend from the ends of the roll and journal in and extend through bearings 16 and 17 formed in the cylinder heads 11 and 12. These spindles extend beyond the heads and are journaled in the bearings 2, one of the spindles extending beyond its bearing 75 and having journaled thereon a driving gear 18, this gear being rotated by suitable means (not shown). Within the cylinder 7 and co-operating with the center roll 14, are intermediate hollow supporting and 80 packing rolls 19, these rolls having end inserts 19^a carrying spindles 20, which spindles journal, preferably a little loosely, in bearings 21 formed in the heads of the cylinder. Both the center roll 14 and intermediate rolls 19 have suitable yielding peripheral surfaces made, for instance of rubber, to provide an effective packing. The periphery of the intermediate rolls engage the periphery of the center roll and the interior periphery of the cylinder, the ends of these rolls being held against the heads 11 and 12. The strain of the web or blanket 4 against the cylinder 7 is in a direction to cause the rolls 19 to press against the center 95 roll 2. I provide, however, additional means for tensioning these rolls against the center roll, and to this end I employ a hollow tension roll 22 positioned within the cylinder 7 and of similar construction generally, to the supporting rolls 14 or 19. This tension roll has its end spindles 23 journaled in suitable bearing blocks 24, which blocks are mounted within alined openings 25 in the heads 11 and 12, and are adjustably held between the spaced ears 26 of said heads by means of adjusting screws 27.

This roll 22 is supported and positioned

whereby it may be moved radially to bear against the inner periphery of cylinder 7 at a point opposite the rolls 19 to thereby force the cylinder against rolls 19 and in turn, cause these rolls to bear strongly against the periphery of center roll 14. The bearing blocks 24 may be moved in the openings 25 in the cylinder heads and radially of said heads to bring the tension roll 22 against the center roll 14 in the event that it is found that said roll sags at the center, as might be the case of a roll of great length.

The ends of the rolls 14-19 bear against the heads of the cylinder as also do the ends of the cylinder. The space below the cylinder and between the rolls 19 and above the center roll 14, is designed to provide a suction space acting upon the paper web under the cylinder between the rolls 19. To this end it is desirable to make this space air tight except for the perforations in the cylinder between the rolls 19, and I have, therefore, provided the following structure. Each of the heads 11 and 12 at alined points, are cored out to provide passages 28 which are utilized to hold a sealing liquid such as water. On the inner faces of the heads, a plurality of liquid feed apertures 29 are provided, these apertures following the line of the passages 28 and communicating therewith from the inner side of the heads. The ends of the cylinder bear against the outer line of apertures 29, and the ends of the rolls 14-19 bear against the inner line of apertures. The contour of each of the cored out passages 28 corresponds to the end outline of the suction space, so that a film of liquid extends around the edges of the suction space at both ends, and is maintained under each of said rolls and between said rolls and the center roll 14. The exterior faces of each of the heads 11 and 12 are tapped as at 30 to provide means for the connection of a pipe (not shown) thereto, which pipe will communicate with the cored out passages 28 and may be used to fill said passages with a liquid such as water.

In order to create suction within the suction space hereinbefore referred to, I provide the head 11 with a flanged outlet pipe 31 preferably of the channel cross-section indicated by the dotted lines in Fig. 5, this pipe communicating with the suction space and having a connection (not shown) with any suitable exhausting apparatus, whereby air is drawn through the perforations in the cylinder 7 between rolls 19 and extracts the water from the paper web passing over the cylinder between these points, and draws it from the interior of the cylinder. The head 12 at the opposite end of the cylinder is provided with an opening 32 normally closed and made air tight by a cover plate 33 suitably secured thereto and removable to per-

mit access to the interior of the cylinder. The cylinder and its heads are mounted for swinging movement in the frames 3. To this end the heads 11 and 12 at alined points are each provided on their exterior faces with interiorly threaded bosses 34, in which are threaded tap bolts 35, which bolts extend through the curved slots in the supporting frames 3, and bear with their heads against said frames to clamp the heads firmly thereto. These slots are curved on arcs concentric with the supporting spindles 15 and with the heads 11 and 12, so that by loosening the tap bolts 35, the heads and their rolls may be adjusted relative to the cylinder, as for instance, when it is necessary to vary the point of suction on the blanket and paper web.

The heads 11-12 are held firmly against the ends of the cylinder and of the supporting rolls by the following means. Head 11 is tapped at two diametrically opposite points as at 36 to receive externally and interiorly threaded bushings 37 having flanged solid heads seating against the outer faces of the head 11. The head 12 at alined points is tapped and provided with bosses 38. Two pairs of complementary tension rods 39 threaded at both ends, are provided. The adjacent ends of each pair of rods have conical sleeves 40 threaded thereon, these sleeves serving as anchorages for the opposite ends of the coiled tensioning springs 41. The free ends of each pair of rods 39 are threaded respectively in the bushings 37 and in the interiorly threaded bosses 38 in the opposite heads 11-12. The rods 39 which engage in the bosses, extend therebeyond and have their ends engaged by tensioning nuts 42 bearing against the bosses 38. By operating these nuts 42, the tension of the springs 41 may be adjusted to give the requisite pressure of the heads 11-12 against the ends of the cylinder.

I have herein described the spindle 15 at one end of the main or center roll 14 as being a driving spindle and having a driving gear 18 journaled thereon. In order to rotate the cylinder 7 from this gear, the following transmission gearing is preferably provided. In the frame 3 at one end of the cylinder, a spindle 43 is mounted and on this spindle is journaled an idler gear 44 meshing with the driving gear 18. Below the spindle 43 a shaft 45 is journaled in the frame 3 and extends from opposite sides thereof. On the outer end of this shaft is fixedly secured a gear 46 meshing with the idler gear 44. The inner end of the shaft 45 extends beneath the gear 10 of the cylinder 7, and has fixedly secured thereto a second gear 47 meshing with this cylinder gear 10 and serving to drive said gear and rotate the cylinder through the train of gearing described. The spindle gear 18 permits ro-

tary adjustment of the cylinder and its heads in the curved slot of the frames 3, as will be obvious.

In paper machinery the width of the web of paper and of the blanket varies with different machines, and unless the entire perforated portion of the cylinder is engaged by said paper web and blanket, air is drawn through the uncovered perforated portion 10 and it is impossible under these circumstances to secure effective suction against the paper web between the rolls 19. To enable the use of one suction cylinder with various widths of paper web and blanket, I may 15 place bands 48 of compressible and expandable material, such as rubber, on the cylinder 7 at opposite ends thereof, the outer ends of these bands pressing against the end flanges 8 and 9 of the cylinder, said cylinder being, in this instance of course, of greater 20 length than is necessary. Holding rings 49 engage the inner edges of these bands, these rings having channels 50 therein and extending annularly thereof (see Figs. 12 and 25 13). In order to hold these rings against the edges of the bands 48 at the desired position and tension, any suitable means may be provided. In the drawings I have shown ears 51 depending from the lower edges of 30 the frames 3 at alined points, the opposite ears having oppositely threaded apertures therein to receive the outer ends of oppositely threaded rods 52. The adjacent and inner ends of these rods 52 may be connected 35 by a turn buckle (not shown). On these rods and adjacent opposite ends of the cylinder, double arm hangers 53 are mounted, these hangers each having interiorly threaded sleeves 54 corresponding to the thread 40 of the rod which they engage. The ends of the arms of the hangers have journaled therein rollers 55 which ride in the channels 50 of the holding rings 49. It will be obvious that manipulation of the turn buckle 45 will move these hanger arms toward and away from the ends of the cylinder, so that the bands 48 may be accommodated to the width of the cylinder which it is desired to cover, and will be held by these rollers and 50 arms in adjusted position.

It will be obvious from the foregoing that I have provided a suction roll wherein powerful and effective action may be had against the web of paper, and wherein various 55 desirable features of construction are provided.

While I have described and shown a specific embodiment of the invention, I desire it understood that the same is susceptible of 60 variation both in structure and relative arrangement of parts, within the spirit of the invention and the scope of the appended claims.

It will be observed that at each end of the 65 roll 14, there is a separate end piece indi-

cated at 14^a. This end piece is provided in the form of a sleeve, preferably of brass, secured in place and so shaped as to minimize friction, the brass running against the end packing instead of allowing the rubber 70 to engage the end packing. These end pieces may be applied to the ends of each of the inside rolls. It will also be noted that the ends of the roll 7 are provided with annular grooves or score lines to reduce friction. I have also found that by providing these annular grooves, a much better joint 75 may be made than when the surface is plain or flat.

What I claim, therefore, and desire to secure by Letters Patent is:

1. In an apparatus of the character described, a perforated rotatable cylinder, relatively stationary heads engaging and closing the opposite ends of said cylinder, means 85 supporting said cylinder located interiorly thereof and providing a suction space therein, and means for adjustably holding each of said relatively stationary heads in contact with the ends of said rotatable cylinder. 90

2. In an apparatus of the character described, a perforated rotatable cylinder, relatively stationary heads engaging and closing the opposite ends of said cylinder, means carried by said heads for supporting said 95 cylinder, including two internally located and spaced cylinder supporting rolls extending longitudinally of the cylinder with their ends engaging said heads, said means providing a suction space between said rolls and 100 beneath that part of the cylinder between said rolls, and means connecting and tensioning said heads against said cylinder ends and against said supporting rolls.

3. In an apparatus of the character described, a perforated rotatable cylinder, relatively stationary heads engaging and closing the ends of said cylinder, means carried by said heads for supporting said cylinder, including two internally located and adjacent 110 cylinder engaging and supporting rolls and a filler to close the space below and between said rolls, said rolls and filler extending longitudinally of said cylinder with their ends engaged by said heads to form a suction 115 space between said rolls and beneath that part of the cylinder between said rolls, and means including an adjustable tensioning spring, for holding said heads tensioned against the ends of said cylinder, supporting 120 rolls and filler.

4. In an apparatus of the character described, a perforated rotatable cylinder, relatively stationary heads engaging and closing the ends of said cylinder, means carried 125 by said heads for supporting said cylinder, including two internally located and adjacent cylinder engaging and supporting rolls and a filler to close the space below and between said rolls, said rolls and filler extend- 130

ing longitudinally of said cylinder with their ends engaged by said heads to form a suction space between said rolls and beneath that part of the cylinder between said 5 rolls, and spring means adjustably connected with said heads and arranged to adjustably tension the same against the ends of said cylinder, supporting rolls and filler.

3. In an apparatus of the character described, 10 a perforated rotatable cylinder, relatively stationary heads engaging and closing the ends of said cylinder, two internally located and adjacent cylinder engaging and supporting rolls carried by said heads and extending longitudinally of said cylinder, a centrally located longitudinally extending internal roll carried by said heads and engaging and closing the space between and below said cylinder supporting rolls, said 15 heads engaging the ends of said rolls and providing a suction space between and above said rolls and beneath that part of the cylinder engaged by said supporting rolls, and spaced tension springs within said cylinder 20 adjustably connected with said heads and arranged to adjustably tension said heads against the ends of said cylinder and said internally located rolls.

6. In an apparatus of the character described, 30 a perforated rotatable cylinder, relatively stationary heads engaging and closing the ends of said cylinder, means carried by said heads for supporting said cylinder, including two internally located and adjacent cylinder engaging and supporting rolls and a filler to close the space below and between said rolls, said rolls and filler extending longitudinally of said cylinder with their ends engaged by said heads to form 35 a suction space between said rolls and beneath that part of the cylinder between said rolls, means for holding said heads against the ends of said cylinder, rolls and filler, and means located interiorly of said cylinder and arranged to be moved to engage said cylinder to hold the same tightly against 40 said supporting rolls.

7. In an apparatus of the character described, 50 a perforated rotatable cylinder, relatively stationary heads engaging and closing the ends of said cylinder, means carried by said heads for supporting said cylinder, including two internally located and adjacent cylinder engaging and supporting rolls 55 and a filler to close the space below and between said rolls, said rolls and filler extending longitudinally of said cylinder with their ends engaged by said heads to form a suction space between said rolls and beneath 60 that part of the cylinder between said rolls, means for holding said heads against the ends of said cylinder, rolls and filler, and means carried by said heads interiorly of said cylinder arranged to be moved in one 65 direction and to one position to engage said

cylinder to hold the same tightly against said supporting rolls, said means being also arranged for movement from said first position to a second position whereby it may engage and brace said filler.

8. In an apparatus of the character described, 70 a perforated rotatable cylinder, relatively stationary heads engaging and closing the ends of said cylinder, means carried by said heads for supporting said cylinder, 75 including two internally located and adjacent cylinder engaging and supporting rolls and a filler to close the space below and between said rolls, said rolls and filler extending longitudinally of said cylinder with 80 their ends engaged by said heads to form a suction space between said rolls and beneath that part of the cylinder between said rolls, means for holding said heads against the ends of said cylinder, rolls and filler, and a 85 roll carried by said heads and located interiorly and extending longitudinally of said cylinder and means whereby said roll may be moved and held in one position to engage said cylinder to hold the same tightly against 90 said supporting rolls and whereby said roll may be moved and held in a second position to engage and brace said filler.

9. In an apparatus of the character described, 95 a perforated rotatable cylinder, relatively stationary heads engaging and closing the ends of said cylinder, two internally located and adjacent cylinder engaging and supporting rolls carried by said heads and extending longitudinally of said cylinder, a 100 centrally located longitudinally extending internal roll carried by said heads and engaging and closing the space between and below said cylinder supporting rolls, said heads engaging the ends of said rolls and providing a suction space between and above said rolls and beneath that part of the cylinder engaged by said supporting rolls, means for holding said heads against the ends of said cylinder and said rolls, and a roll carried 105 by said heads and located interiorly and extending longitudinally of said cylinder and means whereby said roll may be moved and held in one position to engage and hold said cylinder tightly against said supporting 110 rolls and whereby said roll may be moved and held in a second position to engage and brace said centrally located roll.

10. In an apparatus of the character described, 120 a perforated rotatable cylinder, relatively stationary heads engaging and closing the ends of said cylinder, means carried by said heads for supporting said cylinder, including two internally located and spaced cylinder supporting rolls extending 125 longitudinally of the cylinder with their ends engaging said heads, said means providing a suction space between said rolls and beneath that part of the cylinder between said rolls, means for holding said 130

- heads against the ends of said cylinder and of the supporting means therefor, and means carried by said heads and coöperating with the ends of said cylinder and of said supporting means to provide a liquid seal about the edges of said suction space at the ends of the cylinder. 70
11. In an apparatus of the character described, a perforated rotatable cylinder, relatively stationary heads engaging and closing the ends of said cylinder, means carried by said heads for supporting said cylinder, including two internally located and spaced cylinder supporting rolls extending longitudinally of the cylinder with their ends engaging said heads, said means providing a suction space between said rolls and beneath that part of the cylinder between said rolls, means for holding said heads against the ends of said cylinder and of the supporting means therefor, and means carried by said heads and coöperating with the ends of said cylinder and of said supporting means to provide a liquid seal about the edges of said suction space at the ends of the cylinder whereby liquid drawn into said suction space from the exterior of the cylinder forms a sealing film beneath said rolls and within said cylinder. 90
12. In an apparatus of the character described, a perforated rotatable cylinder, relatively stationary heads engaging and closing the ends of said cylinder, means carried by said heads for supporting said cylinder, including two internally located and adjacent cylinder engaging and supporting rolls and a filler to close the space below and between said rolls, said rolls and filler extending longitudinally of said cylinder with their ends engaged by said heads to form a suction space between said rolls and beneath that part of the cylinder between said rolls, means for holding said heads against the ends of said cylinder, rolls and filler, and means carried by said heads whereby liquid drawn into the suction space from the exterior of the cylinder forms a sealing film around the edges of said cylinder, roll and about that portion of the filler ends bounding said suction space at the ends of the cylinder to thereby provide a liquid seal for said ends of the suction space. 100
13. In an apparatus of the character described, a perforated rotatable cylinder, relatively stationary heads engaging and closing the ends of said cylinder, means carried by said heads for supporting said cylinder, including two internally located and adjacent cylinder engaging and supporting rolls and a filler to close the space below and between said rolls, said rolls and filler extending longitudinally of said cylinder with their ends engaged by said heads to form a suction space between said rolls and beneath that part of the cylinder between said
- rolls, means for holding said heads against the ends of said cylinder, rolls and filler, said heads being provided with reservoirs for liquid and having means for feeding liquid from said reservoirs to the edges of said cylinder, roll and filler ends bounding said suction space at the ends of the cylinder to provide a liquid film at such ends forming liquid seals for the ends of said suction space, whereby the liquid drawn into said suction space from the exterior of the cylinder forms a sealing film beneath said supporting rolls and between said rolls and said filler. 75
14. In an apparatus of the character described, a perforated rotatable cylinder, relatively stationary heads engaging and closing the ends of said cylinder, two internally located and adjacent cylinder engaging and supporting rolls carried by said heads and extending longitudinally of said cylinder, a centrally located longitudinally extending internal roll carried by said heads and engaging and closing the space between and below said cylinder supporting rolls, 90 said heads engaging the ends of said rolls and providing a suction space between and above said rolls and beneath that part of the cylinder engaged by said supporting rolls, means for holding said heads against the ends of said cylinder and its rolls, said heads having liquid reservoirs formed therein and being provided with feed ducts positioned to supply a film of liquid to the edges of said cylinder and its rolls bounding said suction space at the ends of the cylinder, thereby forming liquid seals for the ends of said suction space whereby liquid drawn within said suction space from the exterior of the cylinder forms a sealing film beneath said supporting rolls and between said rolls and said center roll. 95
15. In a device of the character described, spaced supports, a perforated rotatable cylinder, relatively stationary heads closing the ends of said cylinder, supporting means for said cylinder carried by said heads and coöperating therewith and with said cylinder to provide a suction space therewith below the same and between said supporting means and said heads, means for journaling said supporting means and heads between said supports and means for adjusting said heads and supporting means about their axis of support and relative to said cylinder to 110 thereby adjust the position of the suction space relatively to the periphery of the cylinder. 115
16. In a device of the character described, spaced supports, a perforated rotatable cylinder, relatively stationary heads closing the ends of said cylinder, supporting means for said cylinder carried by said heads and including two spaced internal rolls engaging and extending longitudinally of the cylinder. 125 130

der, a filler engaging and closing the space between said rolls, said rolls and filler having their ends in engagement with said heads to form a suction space below the cylinder and above said rolls and filler between said heads, means for journaling said supporting means and heads on said supports and means coöperating with a head and its support for adjusting said heads and 10 supporting means about their axis of support and relative to the cylinder to thereby adjust the position of the suction space relatively to the periphery of the cylinder.

17. In a device of the character described, 15 spaced supports, a perforated rotatable cylinder having a gear thereon, relatively stationary heads closing the ends of said cylinder, two spaced internal supporting rolls having their ends journaled in and abutting 20 said heads and a center roll engaging said supporting rolls and closing the space therebetween, said center roll having its ends abutting said heads to form with said cylinder, rolls and heads a suction space, and 25 having end spindles extending through said heads and journaling said head and rolls on said supports, a driving gear journaled on one of said roll spindles, an idler gear carried by the support for said spindle end and 30 engaging said driving gear, a third gear carried by said support, engaging said idler gear and operatively connected with said cylinder gear to rotate said gear and its cylinder, and means coöperating with a 35 head and its support to adjust said heads and rolls about said spindle ends as an axis and relative to said cylinder.

18. In a device of the character described, spaced supports, a hollow cylinder mounted therebetween having perforations therein 40 extending longitudinally and circumferentially thereof, and having its ends closed, means providing a suction space within said cylinder extending longitudinally of said cylinder between its ends and partially 45 around its periphery, means carried by and extending circumferentially and exteriorly of the cylinder and movable longitudinally thereon to cover or uncover suction apertures therein and thereby vary the length of 50 effective suction surface of said cylinder.

19. In a device of the character described, spaced supports, a hollow cylinder mounted therebetween having perforations therein 55 extending longitudinally and circumferentially thereof, and having its ends closed, means providing a suction space within said cylinder extending longitudinally of said cylinder between its ends and partially around its periphery, means carried by and 60 extending circumferentially of the cylinder at each end thereof, said means being compressible and expandable, and manually controlled means coöperating with said compressible and expandable means on said cylinder to move the same longitudinally of said cylinder to cover or uncover suction apertures therein and thereby vary the length of 65 effective suction surface of said cylinder.
